ATTORNEY.

UNITED STATES PATENT OFFICE.

HARVEY L. WATSON, OF INDIANAPOLIS, INDIANA, ASSIGNOR, BY MESNE ASSIGNMENTS, TO C. M. HALL LAMP COMPANY, OF DETROIT, MICHIGAN.

ТИЛТИНГ РЕФЛЕКТОР ДЛЯ МОТОРНЫХ ТЕХНИК.

1,421,630.

Specification of Letters Patent. Patented July 4, 1922.

Application filed February 24, 1920. Serial No. 360,579.

To all whom it may concern:

Be it known that I, HARVEY L. WATSON, a citizen of the United States, and a resident of Indianapolis, county of Marion, and State of Indiana, have invented a certain new and useful Tilting Reflector for Motor Vehicles; and I do hereby declare that the following is a full, clear, and exact description thereof, reference being had to the accompanying drawings, in which like numerals refer to like parts.

The chief object of this invention is to provide a motor vehicle headlight with mechanism for tilting the reflector so as to focus the light rays upon the roadway immediately in front of the vehicle, or straight ahead of the same, as desired.

One feature of the invention is the positive action of the same to actuate and maintain the reflector in either position, as desired.

A further feature of the invention is the improved headlight supporting base or structure.

The full nature of this invention will be understood from the accompanying drawings and the following description and claims.

In the drawings Fig. 1 is a central cross sectional view of the head lamp supporting the tilting mechanism, showing the same in the normal position. Fig. 2 is a similar view but showing the parts in the tilted position. Fig. 3 is a plan view of the actuating mechanism taken in the plane of the line 3—3 of Fig. 1.

In the drawings 10 indicates the usual headlight enclosing casing or hood, and 11 the reflector contained therein. In the present instance the reflector is pivotally mounted and supported by said hood in any suitable manner. Secured to the lower portion of said pivotally supported reflector is a depending bracket member 12, having a portion projecting rearwardly. Positioned beneath said reflector and adjacent thereto upon a suitable bracket or lug 13 supported by and forming a part of the improved tubular base or clamping and supporting structure 14, is a pivoted bell crank lever 15. One end of said lever is connected to said depending bracket 12 through the link arm 16, the same having bifurcated ends engag-

ing respectively the rearward portion of said depending bracket 12 and the before 55 mentioned end of the bell crank lever.

Means for tilting the reflector comprises a projecting lever 17 rigidly secured to a tilting rod, tube or rock shaft 18 by means of a tapered pin 19. The projecting lever 17 60 is herein shown positioned between a pair of projecting lugs 20 formed integral with a standard or base supporting bracket 21, the same supporting the post 14, as shown. The supporting tubular shaft 22 extends 65 transversely of said vehicle and is positioned forwardly of the tilting rod 18 and in substantially the same horizontal plane to protect the same from casual injury. The headlight supporting tube and shaft are suitably supported upon the motor vehicle. The tilting rod or rock shaft 18 is provided with a rocking or actuating lever 24, the same being adjustably secured to the rod by means of the clamping bolt 25. The other end of 70 the rocking lever is attached to a suitable rocking arm or actuating rod 25, the same extending to the dash of the motor vehicle 75 so as to be readily accessible to the driver of the same.

Since, in the present invention the particular mounting of the tubular shaft is immaterial, but one end portion of the assembly is illustrated in Fig. 3 for the other end assembly is identical therewith.

Herein shown integral with the base 14 is a projecting portion 26, the same having an opening therein adapted to receive a sleeve or bushing 27, the same having a threaded exterior. An adjusting nut 28 is 90 adapted to lie adjacent the portion 26 and secure said sleeve in the adjusted position. Extending through said sleeve and slidably longitudinally thereof is an actuating rod or plunger 29, the latter having a head portion 30 adapted to engage the arm portion 31 of the bell crank lever 15, heretofore described. The other end of said plunger 29 is actuated by the projecting or tilting lever 17, the rearwardly extending end thereof 95 being provided with a contact bolt 32 adjustably secured thereto by means of the adjusting nut 33.

From the foregoing description it will be understood that the rocking movement 100 initiated by the actuating rod 25 is trans-

mitted through the lever 24, shaft 18, tilting lever 17 and plunger 29 to the bell crank lever 15 to tilt the same into the position shown in Fig. 2. When the actuating rod 5 is released from the position shown in Fig. 2 and returned to that shown in Fig. 1, the tilted reflector is returned to the position shown in Fig. 1 by means of a coiled spring 34 having its opposite ends suitably 10 secured to the supporting lug 13 and the bracket 12. Said spring also returns the plunger 29 to the position shown in Fig. 1 so that said plunger will contact with the contact bolt 32, as shown, the downward 15 movement thereof being limited by the forward edge 35 of the sleeve 27 engaging the head 30, as shown.

As shown in the drawings, the improved structure or headlight supporting base is 20 stationarily secured in the supporting bracket 21, the same being in turn stationarily secured to the tubular construction 22 by suitable nut means not shown. The base 14, in addition to providing the bearing portion 26 for the tilting plunger, is provided upon the opposite side with a forwardly and depending flange portion 36, said flange extending through said hood. As shown, said flange is suitably slotted to form the bifurcated tongue 37 adapted to receive a pivoted bolt 38, the same secured to said tongue by means of a thumb nut 39. The latch, 25 comprised of the members 37, 38 and 39 secure the forward plate or hinged door 120 of the hood to the same in the locked position. It will also be understood that the supporting base or standard 14 is suitably secured to the hood 10, such that said hood is rigidly supported thereon.

40 With the foregoing construction it will be understood that the headlights may be tilted from the normal position of focusing said light upon the roadway immediately in front of the vehicle to a position wherein 45 the light rays are projected forwardly and the axis of said reflector lies substantially in a horizontal plane.

The invention claimed is:

1. In a lamp construction, the combination with a casing, a door closure therefor, 50 a reflector tiltably mounted within said casing, and means for tilting said reflector within said casing, of a unitary supporting member including a standard portion for supporting a casing, a portion for detachably securing the closure to the casing, and a portion for supporting the tilting means.

2. In a lamp construction, the combination of a lamp casing, a reflector pivotally 60 supported therein, a bell crank pivotally supported in said casing, a link member operatively connecting one end of said bell crank and reflector for tilting the latter, spring means having one end associated 65 with said operative connection for main-

taining said reflector in one position, a sleeve mounted in said casing, a plunger extending through said casing and slidably longitudinally of said sleeve and therein and limited in movement and engaging the 70 other end of said bell crank, and lever means without the casing for actuating said plunger in opposition to said spring means.

3. In a lamp construction, the combination of a lamp casing, a reflector pivotally supported therein, a bell crank pivotally supported in said casing, a link member operatively connecting one end of said bell crank and reflector for tilting the latter, spring means having one end associated 80 with said operative connection for maintaining said reflector in one position; and the other end stationarily secured, a sleeve adjustably mounted in said casing, a plunger slidably longitudinally of said sleeve and engaging the other end of said bell crank and extending through said casing and limited in movement, rocking means without the casing, and adjustable means associated with said rocking means and engaging said 90 plunger for actuating said plunger in opposition to said spring means.

4. In a lamp, the combination with an outer casing, of a reflector therein, a pivotal mounting for said reflector within said casing, a bracket for supporting said casing, a bell crank lever mounted on said bracket in the space between said casing and said reflector, a push rod slidably engaging a bearing in said bracket and in operative relation 100 to one arm of said bell crank, a link for connecting another arm of said bell crank with said reflector to tilt the latter, and a spring connected to said link for retracting the same and tilting said reflector in the opposite direction.

5. In a lamp, the combination with a casing, of a reflector within said casing, a pivotal mounting for said reflector, a bracket for supporting said casing, a bell crank lever within the space between said casing and reflector, a lug integral with said bracket forming a fulcrum bearing for said bell crank lever, a link for connecting one arm of said bell crank lever with said reflector, 115 a spring connected to said link and to said fulcrum bearing for retracting the former, a push rod extending through said casing for actuating the other arm of said bell crank lever, and a stop for said push rod adjustable to determine the normal position of said reflector.

6. In a lamp, the combination with an outer casing, of a reflector therein, a pivotal mounting for said reflector, a bracket for 125 supporting said casing having a hollow shank through which electrical connections may pass, a bell crank lever fulcrumed upon said bracket in the space between said casing and reflector, a link for connecting one 130

arm of said bell crank lever with said reflector, an apertured arm projecting from said bracket, a push rod extending through the aperture in said arm in operative relation to an arm in said bell crank lever, a bearing sleeve for said push rod having a threaded engagement with an apertured arm of said bracket to be adjustable therein, and a head on said push rod normally bearing on 10 said adjustable sleeve, whereby the adjustment of said sleeve will determine the normal angular position of said reflector.

7. In a lamp, the combination with an outer casing, of a reflector therein, a pivotal 15 mounting for said reflector, a bracket for supporting said casing having a hollow shank for the passage of electrical conductors, arms formed integral with said bracket, one constituting a locking lug for the door 20 of said casing and another being apertured, a bell crank lever fulcrumed upon said bracket in the space between said casing and reflector, a link connecting one arm of said bell crank lever with said reflector, a push 25 rod passing through said apertured arm into operative relation to said bell crank lever, a bearing sleeve for said push rod having a threaded engagement with said apertured arm, a spring for actuating said link and 30 bell crank lever counter to the push of said push rod, and a shoulder on said push rod for engaging said adjustable sleeve, whereby the adjustment of the latter will determine the fulcrum position of said reflector.

35 8. In a lamp construction, the combination with a casing, of a reflector pivotally mounted therein, lever mechanism for actuating said reflector, a spring for normally holding said lever mechanism in predetermined 40 position, means for actuating said lever mechanism, and a supporting bracket for

said casing forming a support for said actuating mechanism also.

9. In a lamp, the combination with an outer casing, of a reflector pivotally mounted 45 within said casing, a bracket on the periphery of said reflector, tilting mechanism for said reflector including a pivoted bell crank lever, link and a spring for normally holding them in predetermined position arranged 50 between and independent of the casing and reflector and pivotally connected to said bracket, and a push rod extending out from said casing for actuating said lever mechanism. 55

10. In a lamp, the combination with a casing, of a reflector pivotally mounted within said casing, a bracket attached to said reflector, a link for tilting said reflector, a pin pivotally connecting said bracket and 60 link, a bell crank lever for actuating said link, a push member for actuating said link, and a spring connected to said pin and said bell crank for actuating said link in the opposite direction without stress upon said 65 reflector.

11. In a lamp construction, the combination with a casing, and an angularly adjustable reflector pivotally mounted therein, of mechanism within said casing and attached 70 to said reflector for holding the same in predetermined angular relation relative to said casing, comprising a lever under spring tension tending to tilt said reflector in one direction, an adjustable bearing member and 75 a member slidably mounted therein, engaging and limiting the movement of said levers and adapted to regulate the normal position of said reflector.

In witness whereof, I have hereunto 80 affixed my signature.

HARVEY L. WATSON.
